BY
ATTORNEY

UNITED STATES PATENT OFFICE.

MERLE J. WEST, OF MILWAUKEE, WISCONSIN, ASSIGNOR TO WILLIAM D. KYLE, OF MILWAUKEE, WISCONSIN.

RENEWABLE FUSE.

1,411,946.

Specification of Letters Patent.

Patented Apr. 4, 1922.

Application filed May 20, 1919. Serial No. 298,478.

To all whom it may concern:

Be it known that I, MERLE J. WEST, a citizen of the United States, and resident of Milwaukee, in the county of Milwaukee and 5 State of Wisconsin, have invented certain new and useful Improvements in Renewable Fuses; and I do hereby declare that the following is a full, clear, and exact description thereof.

10 My invention relates to cut-outs for electric circuits, and particularly to cartridge fuses of the renewable or refillable type.

Although cartridge fuses of this form have been known to the trade for a considerable 15 time, so many of them have been defective and inefficient that they have not come into such general use as to supplant the old standard non-refillable fuse. One of the principal objections to the usual refillable fuse 20 is that upon "blowing" sparks and flames are liable to be thrown through unprotected cracks or openings in the wall of the fuse casing. In other words after several refillings the parts of the renewable fuses of ordinary construction become so loosened or 25 worn that leakage of flame is easily possible. Also with such ordinary refillable fuses there is no safeguard against careless reassembling after refilling, and thus a fuse may be 30 replaced in the electric circuit in such condition that the fire hazard is very materially increased.

The principal objects of this invention are, 35 therefore, to provide a protective means which will effectively cover all possible outlets of flame which may occur upon "blowing," and means for rendering the insertion of the fuse in the electric circuit impossible until the parts have been correctly assem- 40 bled.

A further object of the invention is to provide a simply constructed means for preventing excessive arcing after the fusible link has "blown" and also to prevent any arcing 45 whatsoever between the link attaching terminals carried by the ends of the fuse.

A still further object of my invention is to provide an indicating device which will show when a fuse has "blown" without first dis- 50 assembling the device.

With these general objects and advantages in view, it will be seen that the invention resides in the novel features of construction, combination and arrangement of parts which 55 will be hereinafter more particularly de-

scribed and claimed and shown in the drawing in which:

Figure 1 represents an elevational view of a renewable cartridge fuse, parts being broken away and in vertical section to more 60 clearly illustrate the interior construction.

Figure 2 is a detail sectional view of one end of the fuse, and

Figure 3 is a transverse sectional view taken substantially on the plane of the line 65 3-3 of Figure 1.

In the embodiment illustrated, the invention is shown associated with a cartridge fuse of the knife blade type, but it is to be understood that the same may be used in 70 connection with the ordinary ferrule type, and further that various other minor changes may be made in the form and proportion and in the connection of the several parts, without departing from the principles of the invention. In all of its several forms the fuse will consist of an inner or housing casing having an opening covered by a hinged closure whereby the fusible link may be inserted thereinto, and an outer or protective 75 shell telescopingly engageable over the inner casing.

Referring to the drawing and considering the parts of the invention in detail, it will be seen that the fuse includes a cylindrical open ended tube or fibre or other insulating and non-inflammable material which forms the major portion of a casing 1, said tube having an elongated opening formed in its wall intermediate its ends to permit 80 access into the interior thereof after the open ends have been closed by ferrules 3 and 4 respectively. From Figures 1 and 3, it will be noticed that the opening 2 has its opposite ends rounded as at 2' and in width is sub- 85 substantially one-half the circumference of the tube. One longitudinal edge portion of the opening 2 has a cover 5 hinged thereto as at 6, and the other edge portion carries one or more spring fingers 7 for engagement in 90 recesses 8 in the cover for holding the same in locked position. This closure 5 for the opening 2 is substantially of the same configuration as the latter and when in closed position its edge is in abutting relation with 95 the edge of said opening. This provides a very close fit between the opening and its cover and the latter has its outer surface flush with the corresponding surface of the casing 1.

100

105

110

The ferrules 3 and 4 are secured to the ends of the casing 1 by crimping as at 9, and when the fuse is of the knife blade type, they carry the contact blades 10, the latter being 5 preferably secured to the ferrules 3 and 4 in a manner indicated in Figures 1 and 2. That is to say the ferrule 3 for instance has a slot formed in its crown to receive the 10 blade 10 which has a shoulder 11 for engagement with the inner side of the former, the outer portion of the blade being swaged against the crown of the ferrule at a plurality of points as at 12. A reinforcing pin 13 extends through the ferrule, the adjacent 15 portion of the casing 1 and the blade as shown.

The inner end of each blade 10 is designed to form a fuse link attaching terminal 14 to which a fusible link 15 is connected. In 20 their preferred construction, these attaching terminals are bifurcated as at 16 and provided with threaded screw holes to receive fastening screws 17. The ends of the 25 fusible link 15 have openings to align with the openings in the terminals when they are disposed between the furcations; the fastening screws 17 obviously secure the link in place.

All possibility of danger through the 30 leakage of flame between the edges of the opening 2 and its cover 5 is obviated by the addition of an outer protective shell 18 which is of a size slightly greater than the inner casing 1 and is adapted to slide thereon. This protective shell is also formed 35 from an open ended insulating and non-inflammable tube, one end of which is closed by a ferrule cap 19 crimped thereon as at 20, the crown of said ferrule cap having a 40 slot to receive the adjacent contact blade 10. The opposite end of this tube has a reinforcing band 21 adapted to slide beneath a spring retaining collar 22 that is carried by the ferrule 3 and is preferably formed 45 integrally therewith.

In assembling the protective shell on the inner casing 1, the open end of the former is slid over the ferrule 4 and the same moved longitudinally until said reinforcing band 50 engages the retaining collar 22 as above mentioned. When this engagement takes place the crown of the ferrule cap 19 will have come into abutting relation with the crown of the ferrule 4. Thus it will be 55 seen that the outer protective shell 18 extends substantially throughout the length of the inner casing and completely covers the opening 2.

Ordinarily when a fuse link "blows," con- 60 siderable arcing occurs, this even extending to the terminal attaching members, as the parts 14, and as a result they are mutilated and refilling is rendered difficult. To overcome this difficulty I have disposed a 65 carbon block 23 transversely of the inner

casing 1 and substantially midway of the ends thereof, this block being of sufficient size to interrupt the air gap between the attaching terminals 14 to thereby prevent the flow of electricity between these parts. The 70 block 23 is held in position by a spring clip 24 that has its ends 25 disposed through openings in the wall of the casing 1 and then bent laterally as particularly shown in Figure 3. The intermediate portion of the 75 clip rests in a channel 26 formed in the block.

As hereinbefore mentioned the present invention also includes means for indicating the condition of the fusible link 15, that is 80 to say whether or not the same is in operating condition or has been "blown." In providing such an arrangement the block 23 is provided with a central hole for the reception of a cylindrical fibre plunger 27, 85 the inner end of which has a head 28 extended beyond the adjacent portion of the block for engagement with the fusible link 15. The opposite or outer end of the plunger is normally extended beyond the adjacent 90 surface of the block and through a hole 29 in the wall of the casing 1. A second hole 30 in the protective shell 18 is adapted to align with the hole 29 and disposed therein is the intermediate portion of an indicator 95 button 31. Said button 31 is carried by the intermediate portion of a spring plate 32, the opposite ends of which are secured to the wall of the shell 18.

When the fusible link 15 is in operative 100 condition, it bears against the head 28 of the plunger 27 and causes the outer end of the latter to force the button 31 outwardly of the shell 18 as indicated in Figures 1 and 3. As soon, however, as the 105 link is "blown," the tension of the spring plate 32 will be exerted to force the button inwardly so that the latter will be only slightly exposed, thus indicating to an observer that the fuse needs refilling. 110

Said observer may readily renew the fuse after taking the same from the switchboard or cut-out block, by slipping the protective shell 18 from off the casing 1, thereby exposing the closure 5, after which said closure 115 may be opened by releasing the spring finger 7 to permit access to the interior of the fuse. The portions of the "blown" fusible link are removed by taking out the screws 17, after which a new fusible link is inserted. The 120 operations of assembling the several parts of the fuse are then carried out, said operations merely being the reverse of disassembling.

I claim:

1. A fuse comprising a casing having an opening in its side wall, terminal contact members closing the ends of the casing, a closure plate removably disposed to close said opening, a spring collar carried by and 130

- spaced from the wall of the casing adjacent one end, a sleeve slideable around said casing to completely cover the closure plate and the edges of said opening and having 5 a shoulder at one end for engagement with said spring collar, and a fusible link connecting the terminal contact members.
2. A fuse comprising a casing having an opening in its side wall, terminal contact members closing the ends of the casing, a closure plate removably disposed to close said opening, a spring collar carried by and spaced from the wall of the casing adjacent one end, a sleeve slideable around said casing to completely cover the closure plate and the edges of said opening, a cap for 10 one end of the sleeve through which the terminal blade projects, said cap fitting against said blade to form a closure for the end of the sleeve, an annular shoulder at the other end of said sleeve for engagement with said spring collar, and a fusible link connecting the terminal contact members.
- 15 3. A fuse comprising a tubular casing, terminal contact members closing the ends of the casing, a link attaching device connected with each of said members, a block disposed transversely of the casing and seated against one side portion of the latter,
- it being spaced from the opposite side portion, said block having a channel, a spring band disposed around said block and in said channel, the opposite ends of said band being engaged with and secured to said casing, and a fusible link connecting the attaching devices. 35
4. A fuse comprising a casing having an opening through its wall, terminal contact members closing the ends of the casing, a link attaching device connected with each of said members, an anti-arcng block disposed transversely of the casing and crossing the longitudinal plane of the attaching devices, said block having an opening formed there- 40 through and aligned with the opening in the wall of said casing, a plunger slideable through said aligned openings, and a fusible link connecting the contact members and having its intermediate portion engaged with the inner end of said plunger whereby to hold the outer end thereof outwardly of said block, said outer end being disposed inwardly of the block when the fusible link is blown. 45
- 50 In testimony that I claim the foregoing I have hereunto set my hand at Milwaukee, in the county of Milwaukee and State of Wisconsin. 55

MERLE J. WEST.
